FIG. 24.

FIG. 23.

FIG. 25

FIG. 26

FIG. 27

FIG. 28

FIG. 1 is a top plan view of a first embodiment of the metal golf club head of this design.

FIG. 2 is a front elevational view of the metal golf club head of FIG. 1.

FIG. 3 is a bottom plan view of the metal golf club head of FIG. 2.

FIG. 4 is a right side elevational view of the metal golf club head of FIG. 2.

FIG. 5 is a rear elevational view of the metal golf club head of FIG. 2.

FIG. 6 is a left side elevational view of the metal golf club head.

FIG. 7 illustrates a top plan view of a second embodiment of the metal golf club head of this design.

FIG. 8 is a front elevational view of the metal golf club head of FIG. 7.

FIG. 9 is a bottom elevational view of the metal golf club head of FIG. 8.

FIG. 10 is a right side elevational view of the metal golf club head of FIG. 8.

FIG. 11 is a rear elevational view of the metal golf club head of FIG. 8.

FIG. 12 is a right side elevational view of the metal golf club head of FIG. 11.

FIG. 13 is a top plan view of a third embodiment of the metal golf club head of this design.

FIG. 14 is a front elevational view of the metal golf club head of FIG. 13.

FIG. 15 is a bottom plan view of the metal golf club head of FIG. 14.

FIG. 16 is a right side elevational view of the metal golf club head of FIG. 14.

FIG. 17 is a rear elevational view of the metal golf club head of FIG. 14.

FIG. 18 is a right side elevational view of the metal golf club head of FIG. 17.

FIG. 19 is a top plan view of a fourth embodiment of the metal golf club head of this design.

FIG. 20 is a front elevational view of the metal golf club head of FIG. 19.

FIG. 21 is a bottom plan view of the metal golf club head of FIG. 20.

FIG. 22 is a right side elevational view of the metal golf club head of FIG. 20.

FIG. 23 is a rear elevational view of the metal golf club head of FIG. 20.

FIG. 24 is a right side elevational view of the metal golf club head of FIG. 23.

FIG. 25 is a cross sectional view of the metal golf club head of FIG. 5 taken in a plane generally perpendicular to the longitudinal axis thereof, passing through the central portion of the recess and illustrating the recess depth.

FIG. 26 is a cross sectional view of the metal golf club head of FIG. 11 taken in a plane generally perpendicular to the longitudinal axis thereof, passing through the central portion of the recess and illustrating the recess depth.

FIG. 27 is a cross sectional view of the metal golf club head of FIG. 17 taken in a plane generally perpendicular to the longitudinal axis thereof, passing through the central portion of the recess and illustrating the recess depth.

FIG. 28 is a cross sectional view of the metal golf club head of FIG. 23 taken in a plane generally perpendicular to the longitudinal axis thereof, passing through the central portion of the recess and illustrating the recess depth.

I claim:

The ornamental design for a metal golf club head, substantially as shown.
